STABILIZER FOR SUCTION GOVERNORS

Arthur A. Bull, Detroit, Mich., assignor to Handy Governor Corporation, Detroit, Mich., a corporation of Michigan

Application June 8, 1929, Serial No. 369,489

22 Claims. (Cl. 137—153)

This invention relates to governors, and more particularly to governors for hydrocarbon motors of the type actuated in accordance with the flow of fluid in the induction pipe of the motor.

More particularly the invention relates to such governors having an unbalanced valve the closing effort of which is balanced in all positions at a predetermined speed of the motor.

One feature of the invention is the provision of means to augment the closing effort of the governor valve at and near full open position.

Another feature is the provision of means to prevent fluttering of the governor valve.

Another feature is the provision of means to prevent "stealing" or overrunning of the speed for which the governor is set, when the carburetor valve is substantially closed.

Still another feature is the provision of a single device that accomplishes the results of the above mentioned first and second features.

Another feature is the provision of a single device that accomplishes the results of the first, second and third features mentioned above.

To these ends the invention consists of a governor for internal combustion engines including a casing having a conduit therethrough, an unbalanced governing valve in said conduit actuated in a closing direction by the flow of gases therein due to the operation of the engine, and means responsive to the difference between atmospheric pressure and the pressure in said conduit to augment the movement of the valve towards closed position and/or prevent fluttering of the valve and/or prevent overrunning or "stealing" when the carburetor valve is adjacent closed position.

Other objects and features of novelty will be apparent from the description taken in connection with the drawing in which:

Figure 1 is a front elevation of a governor constructed according to the present invention showing the cover plate removed from the chamber housing the mechanism;

Figure 2 is a vertical section on line 2—2 of Fig. 1;

Figure 3 is a vertical section on line 3—3 of Fig. 2; and

Figure 4 is a vertical section through the thimble or cap closing the end of the cylinder.

This invention is particularly directed to an improvement in that type of governor in which the governing valve is unbalanced and arranged in the induction pipe of the engine so as to be actuated toward closed position by the flow of fuel in this pipe. In the specific illustration of

the invention, the control valve takes the form of a butterfly valve 10 arranged in a conduit 11 adapted to be included in the induction pipe of the engine between the intake manifold on the upper side and the carburetor on the lower side, it being assumed that the carburetor is provided with a manually controlled throttle valve. The device of the present invention as a unit is adapted to be secured in position by bolting the upper flange 12 thereof to the flange of the intake manifold and the lower flange 13 to the flange of the carburetor.

The conduit portion 11 is preferably square in cross section in order that the valve may have a better fit and that a large area thereof may be at a great distance from the shaft, since, as particularly shown in Figs. 2 and 3, the valve is of the unbalanced type wherein the larger portion 15 is below the spindle 16 and the much smaller portion 17 above the spindle which is offset from the center of the conduit, as clearly shown in Fig. 3. This condition results in a closing effort being applied to the valve when the fuel flows upwardly in the induction pipe section 11, as will be evident from an inspection of Fig. 3.

This closing effort increases rapidly as the valve approaches the closed position. In the open position the velocity of the fuel flowing through the induction pipe is largely responsible for the closing effort, but as the valve approaches the closed position, there is a change in pressure on the two sides thereof due to the suction of the engine pistons acting on the upper face. The resistance offered to movement of the valve, by a conventional spring, increases directly with the compression or extension of the spring and therefore a spring cannot be connected directly to the unbalanced valve to resist the closing effort of the fuel flow and still have the governor maintain a constant speed of the engine at all loads. The present invention employs any suitable method of applying a spring opposing the valve closing effort so that the two will be balanced for substantially all positions of the valve at a predetermined engine speed and is more particularly directed to the provision of means to provide auxiliary or augmentative effort to aid in closing the valve, and/or preventing "stealing" or overrunning and/or preventing fluttering of the governor valve.

The valve is mounted on the spindle 16 journaled in bearings 18, 18' in the casting 19 forming the main portion of the governor device and carrying the aforementioned flanges 12 and 13. At what may be considered the front end 20 of

the casting 19 is secured to the casting 21, by any suitable joint 22, and forming the mechanism chamber 23 more or less kidney-shaped, as shown in Fig. 1. The shaft 16 extends into this chamber and receives on its end the hub of a crank 24 which is non-rotatably secured thereto. This crank carries at its lower end a stud 25 having journaled thereon a roller 26 which bears along the curved face 27 of the arm 28 pivoted at 28'. 10 to the bottom wall of the compartment housing 23. The opposite end of the arm 28 is pivoted to the link 29 attached to one end of the helical spring 30, the opposite end of which is adjustably secured, as at 31, to the wall of the housing. A 15 boss 32 forms a stop for the lever 24 so that the spring normally holds the valve in the partially closed position shown in Figs. 1 and 3 so that it will always be ready to tend to close upon the flow of fuel.

20 It will be seen that as the valve tends to close, the lever 24 will rotate in a counterclockwise direction, as viewed in Fig. 1, and the lever arm through which it acts on the spring will be increasingly shortened as the roller 26 rolls along the surface 27 and approaches the pivot 28'. This 25 action is modified to some extent by the curvature of the face 27 of the lever 28, which curvature is worked out so that the spring exerts a force in any position of the valve which exactly balances that tending to close the valve at a predetermined engine speed.

25 The governor as just described functions in accordance with known principles in a very satisfactory manner, but it is found that when this type of governor is applied to certain types of engines, there is a tendency for the butterfly valve to oscillate or fluctuate due to the changes in velocity and pressure in the induction pipe as the various pistons come into operation. This is 30 especially noticeable in large four-cylinder engines and it has been found that such oscillation, by constantly vibrating the various parts of the governor, wears the various bearing points quite rapidly. To overcome this difficulty, the present 35 invention contemplates the provision of stabilizer mechanism to steady the valve. This mechanism takes the form of a dash pot, as seen in Fig. 3 and comprises a piston 33 linked to the valve 10 and working in a cylinder 34. The cylinder is conveniently an open-ended tube provided with a reduced end 35 having a pressed fit into a hole 36 in the side of the induction pipe 11. The piston can be of any desired type and is here shown as a trunk piston having the wrist pin 36' which is connected by means of the link 37 to the pin 38 on the clevis 39 riveted to the lower face of the longer arm of the butterfly valve 10.

60 To close the open outer end of the cylinder, resort is had to a punched or pressed metal thimble or cap 40 which has a press or drive fit over the outer wall of the cylinder 34. To permit a restricted flow of atmospheric air to the outer face of the piston, the cylinder wall is provided with several longitudinal grooves 41 in the portion over which the skirt 42 of the thimble fits and this skirt is provided with a plurality of short projections 43 at the free edge thereof which not only prevents the flange 44 at the bottom of the skirt from fitting tightly against the face of the casting 19, but also holds the head portion of the thimble away from the upper edge of the cylinder, as clearly shown in Fig. 3. Furthermore, there is a clearance space 45 at the 65 lower edge of the cylinder so that air can pass

in the spaces between the lugs 43 through the clearance space 45 and up through the grooves 41 and gain access to the outer face of the piston. The amount of air flowing can readily be controlled by the size of the grooves in the outer surface of the cylinder or by the length of the lugs 43, or both, so that any desired dash pot action can be had to give the required damping to the valve.

10 The inner face of the piston 33 is exposed to 10 the sub-atmospheric pressure in the induction pipe and particularly to the sub-atmospheric pressure between the butterfly valve 10 and the throttle valve 46 in the carburetor, not shown. This pressure will vary from nearly atmospheric 15 with full open throttle valve to a fairly low pressure when the manually controlled throttle valve is substantially closed, for the engine suction will then act in the space between the two valves.

15 As is well-known, the closing effort on the 20 governor valve is a minimum when opened as far as permitted, and a maximum when adjacent closed position. As the pressure in the conduit between the governor and manual throttles is always sub-atmospheric due to the resistance to 25 the flow of gases presented by the carburetor throttle valve and the carburetor itself, the difference of pressures on the two sides of the piston 33, that is the pressures inside and outside of the governor, augments and increases the closing 30 effort of the governor valve. When the manual throttle is wide open this augmentative effort aids the nominal weak closing effort of the governor valve, when it is at and near full open 35 position.

40 When the carburetor throttle valve is in a nearly closed position the governor valve 10 will be substantially in its full open position, resulting in a vacuum or negative pressure nearly equal on both sides of the governor throttle valve. The fuel velocity is also very low. Under these conditions the governor throttle valve will tend to remain in a wide open position causing a slight "overrun" in the governor; that is, the speed of the engine under these conditions 45 may be controlled to some extent by the position of the carburetor throttle valve instead of the governor throttle valve. Here the device of the present invention steps in and aids the closing effect on the governor valve. As the suction 50 in the intake conduit above the carburetor throttle valve is increased by the closing of the carburetor throttle valve, it is evident that this reduction in pressure on the inner face of the piston 33 will cause an unbalance of this piston due 55 entirely to pressure differences and not affected by velocity, which unbalance provides an operating force assisting to move the governor valve 10 toward closed position. Hence, in addition to its other functions, the piston 33 becomes effective when the carburetor throttle valve is in a nearly closed position to compensate for the lack of velocity and consequent pressure on the lower face of the governor valve 10.

60 From the foregoing it is apparent that the piston has three functions, first, to damp the action of the governor valve; second, to prevent overrun of the governor when the carburetor throttle valve is substantially closed; and third, to augment the closing effort of the governor valve 70 when the carburetor throttle valve is at or near wide open position and particularly to augment this closing effort when the governor valve is at and near full open position. The whole assembly of this invention can readily be attached to 75

the form of governor shown and can also be applied without departing from the spirit of this invention to other forms of governors working on substantially the same principle as that disclosed, but being materially modified in construction.

Although a specific form of the invention has been described in detail, it is to be understood that it is not thus limited, but includes modifications and changes coming within the scope of the appended claims.

Having thus described the invention, what is claimed as new and desired to be secured by Letters Patent is:

1. The combination with the induction pipe of an internal combustion engine having a manually operable throttle valve therein, of a governor between said valve and the engine cylinders including a governing member in said pipe actuated in a closing direction by the operation of the motor, means opposing said closing movement at a predetermined speed of the motor with a substantially equal effort in all positions of said member, said effort being unequal to the closing effort of the member at other speeds and means actuated by induction pipe pressure only, adapted to apply closing effort to said member only when the pressure on the throttle valve side of the governing member is less than atmospheric.

2. The combination with the induction pipe of an internal combustion engine having a manually operable throttle valve therein, of a governor between said valve and the engine cylinders including a governing member in said pipe actuated in a closing direction by the operation of the motor, means opposing said closing movement at a predetermined speed of the motor with a substantially equal effort in all positions of said member, said effort being unequal to the closing effort of the member at other speeds and means actuated by reduction in pressure in said induction pipe between the throttle valve and governing member to apply closing effort to said member when the throttle valve is nearly closed.

3. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, and means exposed to atmospheric pressure to augment said closing effort at and near full open position of said unbalanced throttle.

4. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, and means to augment said closing effort at and near full open position of said unbalanced throttle, said last mentioned means comprising a member exposed at one side to in-

duction pipe pressure between the two throttle valves and at the other to atmospheric pressure.

5. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, and means to augment said closing effort at and near full open position of said unbalanced throttle, said last mentioned means comprising a piston having one face exposed to the induction pipe pressure existing between the two throttle valves and the other to atmospheric pressure.

6. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, means to augment said closing effort at and near full open position of said unbalanced throttle, said last mentioned means comprising a piston having one face exposed to the induction pipe pressure existing between the two throttle valves and the other to atmospheric pressure, and means to restrict the flow of air to said atmospheric face of said piston so as to cause dash pot action to prevent fluttering of the unbalanced throttle valve.

7. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, a cylinder in the wall of said induction pipe between the throttle valves, a piston in said cylinder having one face exposed to atmospheric pressure and the other to induction pipe pressure, and means operatively associating said piston and unbalanced throttle valve.

8. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, a cylinder in the wall of said induction pipe between the throttle valves, a piston in

- said cylinder having one face exposed to atmospheric pressure and the other to induction pipe pressure, and a link connecting said piston and unbalanced throttle valve, said link being arranged to cause the piston to exert maximum effort on said valve when the valve is fully open.
9. The combination with the induction pipe of an internal combustion engine having a manually operable throttle valve therein, of a governor including an unbalanced throttle valve in said induction pipe, between said manually operable throttle valve and the engine cylinders, normally actuated toward closed position by the velocity of fuel in said induction pipe, yielding means opposing movement of said unbalanced throttle valve, means to balance the closing effort and the effort of the yielding means at a predetermined speed of the engine and all positions of the unbalanced throttle valve, a cylinder in the wall of said induction pipe between the throttle valves, a piston in said cylinder having one face exposed to atmospheric pressure and the other to induction pipe pressure, means operatively associating said piston and unbalanced throttle valve and means restricting the flow of air to the atmospheric face of said piston.
10. A governor having a conduit portion adapted to be secured between the carburetor and intake manifold of an internal combustion engine, a valve in said conduit adapted to be actuated in a closing direction in accordance with the flow of fluid in said conduit, yielding means resisting the closing movement, a dash pot mechanism connected to said valve to prevent fluttering, and means to cause said dash pot to aid with maximum effort the closing effort of said valve at wide open positions of the valve when low fuel velocities exist in said conduit.
11. A governor having a conduit portion adapted to be secured between the carburetor and intake manifold of an internal combustion engine, a valve in said conduit adapted to be actuated in a closing direction in accordance with the flow of fluid in said conduit, yielding means resisting the closing movement, a dash pot mechanism connected to said valve to prevent fluttering, and means to apply the pressure in the conduit on the carburetor side of said valve only to said mechanism to aid said closing effort of said valve.
12. A governor having a conduit portion adapted to be secured between the carburetor and intake manifold of an internal combustion engine, an unbalanced butterfly valve therein, a counter-balancing means connected to balance the turning effort of said valve at a predetermined speed of the engine, a dash pot cylinder in a wall of said conduit, a piston therein, a link connecting said piston to said valve to aid it in closing when low conduit pressure acts on the inner face of said piston, and means closing the outer end of said cylinder but permitting a restricted flow of atmospheric air to the outer face of said piston.
13. A governor for internal combustion engines including an unbalanced governing valve actuated in a closing direction by the flow of fluid therover, and a vacuum responsive means for augmenting the closing effort of said valve, said means being up-stream from said valve.
14. A governor for internal combustion engines including an unbalanced governing valve in the intake duct actuated in a closing direction by the flow of fluid through said duct, resilient means opposing the closing of said valve and vacuum responsive means augmenting the closing effort of said valve, said means being located on the far side of the valve from the engine.
15. A governor for internal combustion engines including an unbalanced governing valve in the intake duct actuated in a closing direction by the flow of fluid through said duct, a manually controlled throttle valve in said duct upstream from the unbalanced valve and a vacuum responsive means to augment the closing effect of said unbalanced valve, said means being actuated in accordance with the vacuum between said valves.
16. A governor for internal combustion engines including in combination, an unbalanced butterfly valve actuated in a closing direction by the operation of the engine, means responsive to the difference of pressures inside and outside of the governor connected to said valve to augment the closing force acting thereon, and means balancing said closing forces at a predetermined speed of the engine.
17. A governor for internal combustion engines comprising a casing having an intake passage adapted for connection with the intake of the engine, an unbalanced butterfly valve in said passage adapted to be actuated toward closed position by the gaseous stream passing toward the engine, means arranged out of the path of travel of the gaseous stream for exerting an additional force tending to close said valve and comprising a piston subjected on one side to the static pressure in said intake passage and on the other to atmospheric pressure, a connection between said piston and valve whereby the valve will be moved toward closed position when the piston is moved by the atmospheric pressure thereon, and resilient means arranged to oppose the closing movement of said valve and having a characteristic substantially that of the combined forces tending to close said valve.
18. A governor for an internal combustion engine comprising, in combination, an unbalanced butterfly valve arranged in the intake passage of the engine and actuated in a closing direction by the flow of the gases to the engine, a cylinder, a piston movable therein, a connection between said piston and said valve, said cylinder on one side of said piston having communication with said intake passage and on the other side having communication with the atmosphere, whereby a differential force is exerted on said piston tending to close said valve, and resilient means arranged to oppose the closing movement of said valve and having a characteristic substantially that of the combined forces tending to close said valve.
19. A governor for internal combustion engines including a casing having a conduit therethrough adapted to form part of the engine intake passage and to be inserted in the intake passage between the usual carburetor valve and the cylinders, an unbalanced governing valve in said conduit actuated in a closing direction by the flow of fluid therover, means responsive to the difference between atmospheric pressure and the pressure in said conduit on the upstream side of the valve for augmenting the closing effort of said valve, and means arranged to oppose the forces tending to close said valve.
20. A governor for internal combustion engines adapted to be inserted in the intake manifold including an unbalanced governing valve actuated in a closing direction by the flow of fluid therover, means responsive to the difference between atmospheric pressure and the pressure inside the governor for augmenting the closing effort of said valve, said means being constructed and arranged

so that its effect is reduced as the valve moves toward closed position, and means arranged to oppose the forces tending to close said valve.

5 21. A governor for internal combustion engines adapted to be inserted in the intake manifold of the engine including an unbalanced governing valve actuated in a closing direction by the flow of fluid through the manifold, resilient means opposing the closing of said valve and means responsive to the difference between atmospheric pressure and the pressure in said manifold for augmenting the closing effort of said valve with decreasing effect as said valve closes.

10 22. A governor for internal combustion engines comprising a casing having an intake passage adapted for connection with the intake of the engine, an unbalanced valve in said passage adapted

to be actuated toward closed position by the gaseous stream passing toward the engine, means arranged out of the path of travel of the gaseous stream for exerting an additional force tending to close said valve and comprising a piston subjected on one side to the static pressure in said intake passage and on the other to atmospheric pressure, means actuated by said piston to move the valve toward closed position when the piston is moved by the difference between said atmospheric and static pressures, and means including a spring and a device to modify the action thereof arranged to balance the forces tending to close said valve at a predetermined speed of the engine for all positions of the valve. ¹⁰
